PLAITING DEVICE

Alice L. Peck, Las Vegas, Nev., assignor to Scovill Manufacturing Company, Waterbury, Conn., a corporation of Connecticut

Filed Dec. 11, 1959, Ser. No. 859,050

1 Claim. (Cl. 223—34)

This invention relates to a device for forming plaits in flexible material, such as fabrics, plastic or the like.

An object of the invention is to provide a simple device which is inexpensive, and easily manipulated by hand, to readily and expediently form plaits in the material.

Another object of the invention is to form a plaiter device which is constructed and arranged to measure the width of the plait as well as to accurately measure the distance between the plaits, or overlap of the plaits.

A further object of the invention is to provide, in the improved plaiter, a space for applying a fixing means, such as a pin, for holding the plait in position and at the same time permitting removal of the device to make the next plait.

Other objects and advantages of the invention will more fully appear from the following description taken in connection with the accompanying drawings in which:

FIG. 1 is a side elevational view of the plaiting device;

FIG. 2 is an edge view of FIG. 1;

FIG. 3 is a view illustrating the first step in manipulating the plaiter device;

FIG. 4 is a view illustrating the turning of the plaiting device to form a plait;

FIG. 5 is a view illustrating the application of a holding device for the plait formed and the removal of the device from the plait;

FIG. 6 is a view illustrating the measuring of the position for applying the device to the material for forming the next plait; and

FIG. 7 is a view illustrating the positioning of the device for forming, and measuring the distance of, overlapping plaits.

Referring to the drawings and particularly to FIGS. 1 and 2, the improved plaiting device comprises a body portion 10 having a pair of blades or tines 12 projecting downwardly therefrom and spaced apart. The tines have parallel outer edges 14. A laterally extending projection 16 at one side of said body portion 10 has a lower edge 18 which is at right angles to an edge 14 of an adjacent tine 12. The edge 18 projects outwardly from the edge 14 a distance equal to the distance between the two parallel edges 14 of the tines 12. A plurality of graduations, here shown as notches 20, are formed along the edge 18.

The device as above described may be formed from sheet metal, plastic or hard rubber and may be stamped or molded to form.

The steps in using the device are illustrated in FIGS. 3 to 7 inclusive. In forming plaits in material 22, preparatory to stitching, the operator applies the device to one edge of the material as illustrated in FIG. 3, with the

2

tines 12 on opposite sides of the material. The plaiter is then turned one hundred and eighty degrees to a position shown in FIG. 4 forming the first plait. A pin 24 is then inserted through the three thicknesses of the material, and between the tines 12, to retain the plait thus formed in location for stitching. The plaiter is then removed, as shown in FIG. 5.

To form an adjacent plait the plaiter is turned back to its original position with the laterally extending projection 16 facing the first formed plait and serves as a measure for locating the next plait. The tines 12 are then positioned on opposite sides of the edge of the material a distance from the rear edge of the first fold equal to the width of the extension 16, the outer end of the edge 18 aligning with the rear edge of the first fold, as shown in FIG. 6, and the process repeated. This assures the proper spacing of each plait and since the length of the edge 18 is equal to the distance between the outer edges 14 of the tines 12 the front edge of the last formed plait will fall in alignment with the rear edge of the previously formed plait.

If it is desired to form overlapping plaits, as illustrated in FIG. 7, the tines 12 are positioned over the edge of the material with one of the graduations or notches 20 aligning with the rear edge of the last formed plait. The amount of overlap is predetermined by a selection of one of the notches.

The plaiter may be made in a variety of sizes depending upon the width of plait desired, and may be merchandised in sets, each set having a range of variable sizes so that the operator has a selection.

By the use of the device each plait is accurately spaced one from another and every plait is of equal width. The device is easily manipulated and is inexpensive to manufacture.

It is my intention to cover by the appended claim such changes as may be included within a reasonable interpretation of the meaning of the terms therein.

I claim:

40 A plaiting device of the character described, comprising a body portion in a single plane, outwardly extending tines integral with said body portion and each having outer parallel side edges, a lateral projection extending outwardly from said body portion at one side thereof, said lateral projection having a width equal to the distance between the outer edges of said outwardly extending tines, and notches in the edge of said lateral projection adjacent one of said outwardly extending tines.
